UNITED STATES PATENT OFFICE.

WILL H. VAN GUILDER, OF NEW ROCHELLE, NEW YORK, ASSIGNOR TO VAN GUILDER,
DOUBLE WALL CO. INC., OF ROCHESTER, NEW YORK, A CORPORATION OF NEW YORK.

MOLDING-MACHINE.

1,250,394.

Specification of Letters Patent. Patented Dec. 18, 1917.

Application filed June 13, 1916. Serial No. 103,442.

To all whom it may concern:

Be it known that I, WILL H. VAN GUILDER, a citizen of the United States, and resident of New Rochelle, in the county of Westchester and State of New York, have invented certain new and useful Improvements in Molding-Machines, of which the following is a specification.

The present invention relates to molding machines, and it has for an object to provide a construction having two or more mold walls connected by a frame or clamp which permits relative movement of the walls so that the machine may be combined with another machine to produce molded corners of different angles, or may be used separately to embrace a window or door frame in order that a wall may be formed in close proximity to the window or door frame.

Another object of the invention is to improve the construction of molding machines to reduce the cost of manufacture thereof and to increase their durability.

To these and other ends the invention consists of certain parts and combinations of parts all of which will be hereinafter described, the novel features being pointed out in the appended claims.

In the drawings:—

Figure 1 is a front view of the machine showing the mold walls in section;

Fig. 2 is a side view of the machine near one end;

Fig. 3 is a perspective view showing two machines connected to form a corner;

Fig. 4 is a perspective view showing two machines connected for forming a pilaster;

Fig. 5 is a plan view of one of the machines;

Fig. 6 is a detail sectional view on the line *a—a*, Fig. 1;

Fig. 7 is a perspective view of the locking device for securing a removable end wall;

Fig. 8 is a perspective view of a removable end wall used with the mold;

Figs. 9 and 10 are perspective views of two cores used with the machine;

Fig. 11 is a perspective of a device for connecting two machines; and

Fig. 12 is a perspective view showing the manner of connecting the end wall with the machine.

Referring more particularly to the drawings, 1 indicates the outer mold walls which, in this instance, are formed of sheet material, the lower edge of which is turned outwardly at 2 and has an angle iron 3 secured thereto. The upper edge of this sheet is bent outwardly at 4 and thence upwardly and outwardly at 5 to provide a hopper extension. To each wall, two uprights 6 are secured, preferably their lower ends being riveted at 7, and their upper ends being extended upwardly through the portion 4 of the wall.

Any suitable means may be employed for connecting the mold walls so as to effect relative movement between the walls. In this instance two pairs of bars or slides 8 and 9 are provided, one member of each pair being arranged above the other member of the same pair, and the members of each pair being connected by bolts 10 operating in slots 11 to permit a relative sliding movement between them.

To the outer faces of the bars 8 and 9, lateral extensions 12 on the uprights 6 are secured by bolts 13, the bolts being adapted to pass through any one of the openings 14 so that the desired distance between the mold walls 1 may be secured.

Any suitable means may be employed for effecting the relative movement between the walls. In this instance, a U-shaped member 15 has its arms 16 pivoted at 17 to the lower slide bar 9 while links 18 are pivoted at 19 to the upper slide bars and at 20 to the arms of the U-shaped member. The swinging of the U-shaped member in one direction moves the walls toward each other, while swinging in the other direction moves the walls 1 away from each other.

There may also be provided a core member between the outer mold walls, this core member being collapsible and being in the form of two inner walls 21 formed of two pieces of sheet metal having their lower ends 22 turned toward each other in overlapping relation, as well as their upper ends 23. Uprights 24 and 25 are secured to the inner faces of the mold walls 21 and have lateral extensions 26 at their upper ends secured to the slide bars 8 and 9. Overlapping plates 24^a and 25^a may be secured to the uprights 24 and 25 to close the ends 10 of the core.

To prevent the collapsing of the core member, the uprights 24 may each be provided with a beveled lug 27, while the uprights 25 may be provided each with a pair of beveled lugs 28 lying in vertical planes on opposite sides of the lug 27 on the adjacent upright 24. To operate between the projections or lugs 27 and 28 locking bars 29 are suspended from pivots 30 on the links 18, 10 and have each a pair of laterally-turned flanges 31 at their lower ends for co-operating with the lugs 28 to prevent lateral movement of the locking bars.

With the end in view of providing mold chambers, beyond the ends of the mold walls 1 and 21, the molding machine is provided with walls or extensions 32 preferably in the form of slides guided between the uprights 6 and the mold wall 1 and between 15 the outwardly-turned portions 2 and 4 on the mold walls 1. These slides or extensions 32 are preferably removable from the machine so that extensions of other lengths or shapes may be employed. Means is also 20 provided for securing the slides in their adjusted positions on the machine, this means in this instance comprising a hand nut 33 operating on a bolt 34 which projects from the wall through a slot 35 in the plate, the slot opening in the end of the 25 plate to permit the removal of the plate without removing the bolt. The uprights 6 are secured in spaced relation from the ends of the walls 1 so that the slide extensions 32 may be moved inwardly within the 30 edge of said mold walls 1.

On an end of each of the slides 32 reinforcing strips 36 are employed having lateral eyes 37 arranged in vertical alinement, 35 so that the slides on two machines may be connected by a connecting piece 38, shown in Fig. 11, having a hand portion 39 and two pairs of hooks or projections 40, each pair connecting two lugs 37 on different 40 machines.

In Fig. 3 two machines are shown connected for forming a corner, the slides 32 at the inner portion of the corner not being projected from the walls 1 as far as the 45 slides 32 at the outer portion of the corner. In this construction, the slide 32 is of greater length than that shown in Fig. 2, and is provided with an additional slot 35 so that the slide may be moved inwardly 50 to the extreme limit. Of course the machine with such a slide must be longer than that illustrated in Fig. 2. For forming the air space in the angled corner, an angled core 41 may be provided which has plates 42 55 projecting from its ends and resting upon seats 43 formed on the uprights 24 and 25. An angle iron 44 may be arranged within the mold at the outer corner, this angle iron being set upright, and, in forming the corner, the machine being guided thereby. This

makes it possible with the smallest amount of labor to secure a corner which is plumb in every respect.

In Fig. 4, two machines are connected for forming a chimney, flue or pilaster. The 70 slide 32 of one machine is extended and connected to the unextended slide of the other machine. The other two proximate slides 32 are not withdrawn but are connected by a pilaster attachment. This attachment 75 comprises preferably a front plate 45 adjustably connected by slots 46 and thumb-nuts and bolts 47 with lateral portions 48 on two end walls. Each of these end walls 80 comprises two sections 49 and 50 adjustably connected together, the section 49 having slots 51 and the section 50 having bolts 52 adjustable in said slots 51. The section 50 carries two depending alined pintles 53 which are adapted to enter the alined eyes 85 37 on the adjacent slide 32. This arrangement permits a pilaster or flue to be formed having any suitable width and any suitable depth. The corners of the pilaster are defined by angle irons 44 which are set upright in the manner described as to Fig. 3. The air space in the pilaster may be formed by a core 54 having plates 42 resting upon the seats 43 at the adjacent ends of the two 90 machines.

For forming flat walls at doorways, windows, or the like, an end wall 55 may be employed. This wall has two pairs of horizontal slots 56, each slot having a plurality of recesses 57 in its lower wall. A pair of 100 locking members 58 secures the end wall 55 to the machine, these locking members being in the form of plates having lateral projections 59 with depending pintles 60, the depending pintles being alined. These pintles 105 are adapted to be passed through the eyes 37 on the ends of the slides 32 in the manner shown in Fig. 12 for the purpose of locking the end wall 58 to the slides 32.

In molding a straight wall, the machine 110 is set in position on cross-pieces 61 so that the parts occupy the position shown in Fig. 1. The plastic material is then introduced into the mold and suitably tampered, after which the operating member 15 is swung to 115 move the walls 1 away from each other and the walls 21 toward each other, thus expanding the mold and collapsing the core. The forming of corners employs two machines connected as shown in Fig. 3, while 120 the forming of pilasters employs two machines connected as shown in Fig. 4.

A molding machine constructed in accordance with this invention is inexpensive to manufacture and simple to operate. It is 125 not only possible to form straight walls but attachments are provided which permit the machine to form corners, pilasters, and many other wall portions which are impossible to make with an ordinary straight wall ma- 130

chine, such as those portions of a wall adjacent a window or door frame.

What I claim as my invention and desire to secure by Letters Patent is:—

5 1. The combination with a pair of uprights, a connection between the upper ends of the uprights permitting a relative movement between said uprights, and manually operated means connected with said connection for effecting such relative movement, of a pair of mold walls slidably mounted on said uprights, to project different distances from one side thereof.

15 2. The combination with a pair of mold walls and connecting means between said walls arranged above them and permitting a relative movement between them, of walls independently movable on said mold walls and each adapted to be projected different 20 distances beyond the mold walls to extend the molding chamber of the machine.

25 3. The combination with a pair of mold walls and connecting means between said walls permitting a relative movement between them, of a pair of slide walls having independent movement on said walls and adapted to be projected beyond said walls to extend the molding chamber.

30 4. The combination with a pair of mold walls and connecting means between said walls permitting a relative movement between them, of a pair of slide walls having independent movement on said walls and adapted to be projected beyond said walls to 35 extend the molding chamber, and means for locking said slide walls in their adjusted positions.

40 5. The combination with a pair of mold walls, each formed from sheet metal with flanges at its upper and lower edges, of uprights secured to the lower flanges and extended through the upper flanges, connecting means between the extended portions of the uprights, and extension slides arranged 45 to move between the uprights and the mold walls.

50 6. The combination with a pair of mold walls, each formed from sheet metal with flanges at its upper and lower edges, of uprights secured to said walls in spaced relation to the walls and also to the ends of the walls, connecting means between the uprights, and extension slides arranged to move between the uprights and the mold walls, 55 and having eyes at their ends arranged to move within the edges of the mold walls.

7. In combination in a mold having two connected walls movable toward and from each other; two independently movable 60 slides movable to lie within the edges of said mold walls or to project from one end of the mold to form an extension chamber.

8. In combination in a mold having two connected walls movable toward and from each other, two independently movable 65

slides adapted to be projected from one end of the mold, said slides having slots therein, and clamping bolts on said mold for operating in the slots.

9. The combination with a mold having two relatively movable outer mold walls, a collapsible core between said mold walls, and connecting means arranged above the mold walls and the core for collapsing and expanding the latter and moving the mold walls relatively, of two slide walls movable independently to extend the molding chamber beyond the end of the collapsible core.

10. The combination with a mold having two relatively movable outer mold walls, a collapsible core between said mold walls, and connecting means arranged above the mold walls and the core for collapsing and expanding the latter and moving the mold walls relatively, of two slide walls movable independently to extend the molding chamber beyond the end of the collapsible core, and a supplemental core having means for supporting it on the end of the collapsible core.

11. The combination with a pair of mold walls each having a plurality of aligned eyes thereon, of a connecting member having two sets of aligned projections, each set being arranged to fit within the eyes of one mold wall.

12. A connecting member for two mold walls, each having aligned eyes, comprising two sets of aligned projections.

13. The combination with two molding machines, and means for connecting them to form a corner, of an angle iron arranged at the corner-forming portion of the machines and acting to define the position of the machines with reference to the corner to be formed.

14. In combination with a molding machine having a pair of outer walls and means for moving said walls toward and from each other; a collapsible core arranged between said mold walls and having two walls, one provided with two projections, and the other provided with one projection, and a locking bar connected to the means for moving the outer walls and adapted to move between the projections on the two walls, said locking bar having flanges for coöperating with those two projections which are arranged on one wall.

15. In combination with two molding machines, a connection between them for forming a pilaster comprising two adjustable end walls connected to the machines and projecting to one side of them, each end wall having an outwardly-turned portion, and a front wall abutting the outwardly-turned portions of the two end walls and adjustably connected to said portions.

16. An end wall for molds having two slots arranged parallel and each provided

- 4
- with a plurality of notches in one wall, each notch of the lower slot being vertical beneath a notch in the upper slot, and a locking bar having a pair of projections arranged to pass through the notches and to be guided in the slots, said projections each having a pin thereon alined with the pin on the other projection.
17. In combination with two molding machines each embodying a frame, and two mold plates longitudinally adjustable on such frame, of means for connecting the walls of the two molds together to form an angular mold chamber.
18. In combination with two molding machines each embodying a frame, and two mold plates longitudinally adjustable on such frame, of means for connecting the

walls of the two molds together to form an angular mold chamber, and a core conforming to said angle and supported by the two frames in said chamber.

19. The combination with two molding machines each of which embodies a frame and two longitudinally adjustable walls, of means for connecting said walls of the two machines, and a core supported at its ends on the two frames.

20. The combination with two molding machines, each of which embodies a frame and two longitudinally adjustable mold walls, each provided at one end with alined eyes, of a device removably fitting into said eyes of two walls of the machines for connecting said walls.

WILL H. VAN GUILDER.
